INVENTOR
PETER VANDENOEVER
BY

ATTORNEY

UNITED STATES PATENT OFFICE.

PETER VANDENOEVER, OF MINOT, NORTH DAKOTA.

GLOBE PROTECTOR.

Application filed April 2, 1928. Serial No. 266,744.

This invention relates to protectors and securing devices for light globes, and the primary object is to provide means of a novel, efficient and practical nature for this purpose, 5 and which is particularly adapted for use in connection with comparatively large and expensive globes such as are employed in street lighting. Further and more specific objects will be disclosed in the course of the following specification, reference being had to the accompanying drawing, wherein:

Fig. 1 is a perspective view of a street light globe which is secured by my improved protector.

Fig. 2 is a plan view of the globe and protector.

Fig. 3 is a sectional view as on the line 3—3 in Fig. 2.

Referring to the drawing more particularly and by reference characters, A designates a base or standard having a flange B, in which the rim C of a globe D is customarily secured by radially adjustable screws (not shown) in the flange B. The screw method of fastening globes is notoriously old in the art, as are also its many objections. Thus, if the screws are a little too tight they will crack the globe. If they are not quite tight enough, the globes will be loose enough to rattle and 30 vibrate under the action of the wind until they soon break; and, it not infrequently happens that the globes are completely lifted out and carried away, with attending dangers. The process of removing and resecuring the globes is a very slow one, and when 35 the screws rust in, as is frequently the case, the process becomes difficult and expensive as well.

To overcome these difficulties and objections I remove the screws entirely, when such are present, and insert a resilient pad or ring E in the flange B. This pad or ring serves as a seat for the globe D, and in so doing provides a slightly resilient support for the globe 45 and also effects a tight joint so that dust and dirt cannot enter and soil or cloud the inner surface of the globe.

The globe is held in place by a capping ring F and three wires G, H and J, all of 50 which are made from strong wire so as to firmly hold the globe in place, and, at the

same time, are practically invisible when the lights within the globe are lit. The ring F is provided with ears or loops K to which the upper ends of the wires are pivotally secured. 55 These loops not only properly space the wires, but give an added resiliency to the ring.

The wires G and H are pivotally anchored at their lower ends, as at L, to parts of the 60 base A, such as eyes or ears M. The lengths of these wires remain fixed after the device has once been properly adjusted. The wire or keeper J is provided with a spring N having a hook O that detachably engages an eye 65 or lug P, that is similar to M.

Normally the spring N, together with the 70 resilient nature of the ring F, causes the wire keepers to hold the globe firmly down in place upon the pad E, and when so held it is obvious that the globe can not vibrate, crack, break or be accidentally removed. To remove the globe, for cleaning or other purposes, it is only necessary to unhook the hook O, whereupon the entire device may be swung 75 over (from the centers L) and the globe may be lifted off. To resecure the globe it is only necessary to replace it and resecure the hook O.

It is understood that suitable modifications 80 may be made in the general design and structural details of the invention as herein shown, provided, however, that said modifications come within the spirit and scope of the appended claims.

Having now therefore fully shown and described my invention, what I claim to be new and desire to protect by Letters Patent is:

1. The combination with a globe and its support, of a pad carried by the support and forming an annular seat for the globe, a ring capping the globe, and spaced keepers connecting the ring to the support, one of said keepers being detachably connected and the other keepers being pivotally connected to the support. 90

2. The combination with a globe and its support, of a pad carried by the support and forming an annular seat for the globe, a ring capping the globe, and spaced keepers connecting the ring to the support, one of said keepers being detachably connected and the 100

other keepers being pivotally connected to the support, said detachably connected keeper consisting, in part, of a spring.

3. The combination with a globe and its support, of a pad carried by the support and forming an annular seat for the globe, a ring capping the globe, and spaced keepers con-

necting the ring to the support, said ring having loops at the points of connection with the keepers whereby to render the ring ¹⁰ slightly flexible between said points of connection.

In testimony whereof I affix my signature.

PETER VANDENOEVER.
